Primary Examiner — Bridget L Eland*Assistant Examiner* — Lauren McVey(74) *Attorney, Agent, or Firm* — Lerner, David, Littenberg, Krumholz & Mentlik, LLP(57) **CLAIM**

The ornamental design for a seal press, as shown and described.

DESCRIPTION

FIG. 1 is a front perspective view of a seal press;
FIG. 2 is a left side view thereof;
FIG. 3 is a right side thereof;
FIG. 4 is a front view thereof;
FIG. 5 is a rear view thereof;
FIG. 6 is top view thereof;
FIG. 7 is a bottom view thereof;
FIG. 8 is a front perspective view of the seal press in a fully assembled state;
FIG. 9 is a left side view thereof;
FIG. 10 is a right side view thereof;
FIG. 11 is a front view thereof;
FIG. 12 is a rear view thereof;
FIG. 13 is top view thereof; and,
FIG. 14 is a bottom view thereof.

The wire frame lines shown throughout the views are intended to indicate surface contour and are not intended to be surface ornamentation.
